ANTHONY BIZZARRI, OF NEW YORK, N. Y.

LUBRICATING DEVICE AND THE LIKE

Application filed August 8, 1927. Serial No. 211,284.

My present invention relates to pumps, particularly but not exclusively pumps for the transmission of lubricant and other fluids, especially for heavy oils and greases, and aims 5 to devise appliances of the general character specified which are simple in construction; which may be readily and economically fabricated and assembled; which consist of relatively few parts; which are compact in construction; and which in operation are characterized by their high speeds and the consequently high pressures which may readily be obtained with such pumps. The appliances of the present invention are further characterized by the economy in time and labor resulting from the use of such pumps, such pumps being immediate in their action both in the application of the lubricant or other fluid and in the speed with 10 which such operation may be interrupted. The appliances of the present invention are further characterized by their capacity for delivering relatively large quantities of lubricants at high pressures in a given time, and by their long life, durability and their little 15 likelihood to get out of order and require repair. In one of their embodiments, the pumps of the present invention are characterized by their combining a series of pumps 20 of different constructions, or of the same construction, used for different purposes, or for the same purpose, but all preferably driven from a single driving element. It is, however, to be clearly understood that this form 25 of pump constitutes but one specific embodiment of the present invention. It is further to be understood that other objects and advantages of the appliances of the present invention will in part be pointed out in detail 30 hereinafter and will in part be obvious to those skilled in the art to which the present invention relates.

In the accompanying specification I shall describe, and in the annexed drawings illustrate, an illustrative embodiment of the present invention. It is, however, to be clearly understood that my invention is not limited 45 to the specific embodiment thereof herein shown and described for purposes of illustration only. It is further to be understood

that the present application is a continuation in part of my previously filed co-pending application, Serial No. 148,359, filed November 15, 1926 and entitled "High pressure pumps".

55 Referring to the drawings wherein I have illustrated the aforesaid illustrative embodiment of the present invention:

Fig. 1 is a side elevation of said embodiment of the present invention, shown partly broken away to show certain portions of the construction more clearly;

Fig. 2 is a longitudinal sectional view of the grease or lubricant pump near the bottom of its stroke, with some of the parts broken away to make the showing clearer;

Fig. 3 is a view similar to that of Fig. 1 showing the pump near the top of its stroke; and

Fig. 4 is a sectional view, partly in elevation, showing the air or other fluid pump forming a part of said embodiment substantially in longitudinal section and also showing portions of the grease or lubricant tank in longitudinal section.

75 Referring now to the aforesaid illustrative embodiment of the present invention, and more particularly to the drawings, illustrating the same, 10 indicates a source of power, such as an electric motor 11, supplied with current from the cable 12 and preferably supported on a track 13 having the wheels 14 and the tail 15 to permit the device to be readily moved around from place to place as desired.

85 The motor 11 has the bracket 20 having the reduced portion 21 and is also provided with the shaft 22 onto which the eccentric, shortly to be described, may be readily slipped and from which it may as readily be removed, such eccentric having a loose fit on the shaft end 22 but without being so tight as to prevent its ready removal and as ready application.

95 Carried by the motor 11, as by being supported on the central portion 16 of the framework of the motor, is a saddle 30 which may, by means of the screws 31 or other suitable fastening means, be readily attached to the motor frame 16, in a manner which will be 100

more fully described later in the specification. 32 indicates the tank bottom which may have integrally cast therewith or otherwise securely attached thereto the saddle 30 5 already described. The tank bottom 32, forming a part of the tank generally designated by reference character 33 and which is intended to contain the lubricant or like fluid or material, preferably includes the outer flange portion 34 having the inner tapered face 34'. The lower portion of the bottom member 32 is hollowed out as indicated by reference characters 35 and 36, and is provided with the ledge 37 on which the main 10 portion of the tank rests and with the ledge 38 on which the wire screen or other filter 39 rests. The bottom member 32 is likewise provided with the delivery port 40 for delivering grease or lubricant or other material to 15 the grease pump shortly to be described.

Adjacent to its central portion, the bottom member 32 is provided with the central hollow or substantially cup-shaped boss 41, which is internally threaded, as at 42, to receive 20 the lower threaded end 43 of the hollow clamping member 44. Communicating with the bottom of the cavity 41', within the boss 41, is an inlet port 45 for the admission of air or other suitable fluid under pressure, 25 which enters the interior of the tank by means of the port 46 near the top of the hollow clamping member 44, which is provided with the manipulating handle 47.

The main tank portion 48 of the tank 33 30 has sweated thereto, or otherwise securely attached to the exterior of the lower edge portion of the tank member 48, a tapered ring-shaped or annular member 49, which is shaped to cooperate with the internal tapered 35 surface 34' of the flange 34 of the bottom member 32. The screen filter 50 is adapted to fit over the upper end of the tapered boss 41 and to be retained thereon with sufficient security, while still permitting the filter 39 40 to be readily removed when the tank member 48 is removed for cleaning the device, or for replacement.

51 is a follower having the central boss 52 permitting the follower to receive and be 45 guided along the hollow clamping member 44, the follower 51 having the outer flange portion 53 contacting with the inner wall of the tank 48. 54 and 55 indicate handles for the manipulation of the tank member 48, the 50 upper or head portion 56 of which is preferably sweated or otherwise securely fitted onto the tank member 48 so as to render the tank air and liquid tight, a feature which is further rendered possible by means of the construction of the lower end of the tank already 55 described.

One of the features of the embodiment of the present invention now being described, is that I combine in one and the same structure a plurality of pumps; preferably pumps

of different types of construction, although pumps of similar types of construction may be employed, and particularly pumps which may be adapted to different types of fluids, although pumps for pumping the same kinds of fluid may be employed. Another feature of the aforesaid embodiment of the invention is that these pumps, whether two or more in number, are preferably driven by means of one and the same driving element, the construction and arrangement of the parts being such that great speeds and great pressures are rendered possible in a very efficient and simple manner.

In the form here being described by way of example merely, one of the pumps is an air pump for creating air pressure above the follower 51 for forcibly feeding the grease or other lubricant into the other pump, which is preferably a grease pump. Thus the plurality of pumps embodied in the device now being described are functionally as well as mechanically interrelated. It may be that a third pump might be used in connection with the other two, such as an oil pump driven from the same driving element and serving to lubricate the other two pumps and also, if so desired, the electric motor itself. However, I have not shown this particular construction since it is not a part of the present invention.

Turning now to the pump constructions briefly referred to above, 60 indicates an eccentric housing including the cup-shaped sleeve 61 and the eccentric pin or boss 62. 63' is a key sweated or otherwise securely attached to the inner surface of the eccentric cup 61 so as to fit with sufficient snugness over the flattened or segmental-circular end of the motor shaft 22. Carried by the eccentric pin or boss 62 is a ball bearing 64 comprising the inner raceway 65, the outer raceway 66, and the ball 67 between the inner and outer raceways 65 and 66, respectively.

The eccentric 62 is adapted to rotate within the eccentric housing 60 comprising the tubular or nipple portion 68' fitting over the eccentric sleeve 61 and the shaft bracket 21, and the removable head 69 adapted to be attached, as by means of the screws 69' to the main portion of the eccentric housing 68. 68' is a steel ball in contact with a portion of the ball bearing 63, as against a point corresponding to the center of rotation on the inner raceway 64, so as to serve to maintain the eccentric 60 and the ball bearing 63 in proper adjusted position.

Communicating with the eccentric housing 68 are a plurality, here shown as two, of pump housings or piston cylinders, one for each of the pumps communicating with the eccentric housing 68 and adapted to be driven by the eccentric 60 and the associated ball bearing 63. As already indicated above, there may be more than two such pumps, but I have, for

purposes of illustration merely, shown but two such pumps in the present example.

Turning now for the time being to the air pump, generally designated by reference character 70, the same comprises a pump housing 71 communicating at its lower end with the eccentric housing 68 and having the piston cylinder or casing 72. Within the piston cylinder or casing 72 is the removable sleeve 73 having the channeled portion 74 for the purpose of providing space for lubricant, a plurality of passages 75 being provided which permit the lubricant in the space 74 to come into contact with the outer wall of the piston, generally designated by reference character 76. It may here be stated that the lubricating space 74 may communicate with a force feed lubricating system, so that the sleeve 73 and the cylinder casing 72 may be oil cooled, for which purpose an additional or a lubricating pump not here shown, may be employed, operated by the driving mechanism already described.

The piston 76 is preferably of the mushroom or hollow, open-ended type to provide for the greatest length of spring possible within the space allowed, as will hereafter be more fully described. Attached to the inner face of the piston 76, as by being integral therewith, is the piston rod 77 which may be hollow but is here shown as being of the solid type.

It may here be stated that the removable sleeve 73 may be made of cast iron. Its removability is a very useful feature, since it permits the sleeve to be removed when it is worn and to be replaced with a new sleeve so that the pump may be restored to its original state of accuracy, proper fit and efficiency.

Below the removable sleeve 73 is the spring retainer 78 in the form of a cup-shaped member having the side wall or substantially cylindrical portion 79 with the perforated upper or head portion 80 and the lower or flange portion 81 by means of which the spring retainer 78 is held in position with the flange portion 81 below the inner end of the removable sleeve 73.

82 indicates a follower which is adapted to reciprocate within the follower chamber 83 formed in the lower portion 71 of the air pump 70. The follower 82 is in the form of a cup-shaped member, having the side wall or substantially cylindrical portion 84, the bottom portion 85 and the lower flange portion 86. 87 indicates a removable pin which passes through a hole 87' through the lower end of the piston rod 77 and against which is placed the bottom portion 85 of the cup-shaped follower 82, said bottom portion being so maintained by means of the spring 88 which extends between the inner face of the portion 80 of the retaining member 78 and the inner face of the portion 85 of the follower member 82.

Due to the length of the spring 88, rendered possible by the construction described above, the spring is characterized by its great capacity, its long life, and the smoothness and uniformity of its action. The lower end 77' of the piston rod 77 bears operatively against the ball bearing 62 carried by the eccentric 60. It will be noted that the movement of the piston 76 is strictly rectilinear. That is, the usual side thrust, with the resulting frictional losses and rapid wear, to be found in the ordinary type of piston operated by a crank shaft will be avoided in the construction described above.

89 indicates the valve head provided with the inlet valve 90 cooperating with the valve seat 90' and provided with the spring 90''. 91 indicates the outlet valve which cooperates with the seat 91' and the spring 91''. The valve fitting 89 is readily removable as a whole for the replacement or repair of any of its parts or for access to the other parts of the air pump structure. For this purpose the lower portion of the fitting 89 may be threaded for cooperation with the similarly threaded inner portion at the upper end of the sleeve 73. 92 indicates an internally threaded collar which fits over the flange 89' of the fitting 89 to hold the same in place.

The outlet valve 91 of the air pump 70 communicates by means of the threaded coupling 93 and the air hose 94, which has the coupling 95 at its other end, with a channel 96 in the bottom member 32 of the grease tank 33. The channel 96 communicates with the inlet port 45 and thus with the interior of the hollow clamping member 44 which, by means of the outlet port 46, permits air pressure to be applied to the follower 51 and thus to the grease within the tank 33.

Likewise communicating with the eccentric casing 68 and adapted to be operated by the eccentric 60 within such casing, is a grease pump generally designated by reference character 100. The grease pump is, as already indicated above, preferably of a different construction from the air pump 70, although intended to be operated by the same mechanical means and substantially in the same manner as the air pump 70. As already indicated above, the various pumps communicating with the eccentric casing 68, of which two are here shown by way of illustration merely, are arranged substantially radially or at an angle with respect to each other.

The pumps are not strictly geometrically radially disposed with respect to each other, since I prefer that, as clearly shown in Fig. 4 of the drawings, the axis of each cylinder and cylinder rod of each pump shall be offset with respect to the center of rotation of the motor shaft 22. I prefer this arrangement since I have found that by means of it the speed of the pump is accelerated and its efficiency substantially increased. In other

words, there appears to be a marked increase in speed and efficiency of the pumps when the axes of the pistons are offset with respect to the center of rotation of the motor shaft 20.

I prefer also that where a plurality of pumps, all driven by the same driving element, as by means of the single ball bearing eccentric 60 within the eccentric casing 68, are employed, their relative displacements shall be so chosen and selected that, while the speed of each pump is the same, the relative amounts of fluids displaced by the respective pumps shall bear the proper relation to each other.

In the example given, the displacement of the air pump is several times, as 15 or 20 times, that of the grease pump. This proportion may, however, be varied at will, dependent upon the character of the pumps and the work to be done by them, as well as by their relation to each other. In any event, the displacements of the pumps are so chosen as to meet the particular requirements of each pump and of the relation which each pump bears to the other pumps in the system.

Returning now to the grease pump, which is more clearly shown in Figs. 1, 2 and 3 of the drawings, the grease pump 100 preferably comprises the plunger cylinder 101 within which reciprocates the plunger 102. This latter is preferably hollow, in order to provide a maximum length of spring, as already indicated above, so as to provide a structure which is durable and uniform in its action. The upper end 103 of the plunger 102 is open while the lower end is closed by the plunger end portion 104 which is sweated or otherwise securely attached in the lower end 105 of the plunger 102. The inner portion 106 of the plunger end 104 is preferably of reduced diameter and is threaded, so as to receive in its threads the lower end 107 of the spring 108, which extends to the top of the cylinder wall 109 within the cylinder 101.

110 is an inlet pipe for grease or the like communicating with the outlet port 40 for grease at the bottom of the bottom plate 32 of the tank 33. The pipe 110 communicates with and is fitted into the inlet nipple 111 which in turn communicates with the inlet port 112 of the grease pump 100. While the inlet port 112 is smaller than the bore of the pipe 110 and the nipple 111, it is still preferably substantially larger than the diameter of the plunger 102 so that a substantial amount of grease will flow into the interior of the pump 100 through the port 112 so as to maintain the pump at its maximum efficiency.

113 indicates a relief valve which may serve as a primer while 114 indicates the outlet from the pump. It will be noted that the pump uses neither an induction valve nor an eduction valve. It will be noted further that the plunger 102 serves as a piston cut-off valve to retain the grease within the cylinder space

above the plunger 102. It may here further be stated that the hollow plunger 102 becomes quickly filled up with grease which serves to lubricate the spring 108 and serves also to make of the hollow plunger 102 which is virtually a solid plunger or piston for the expulsion of the grease or the like.

115 indicates a cap screw which is screwed into the upper end 116 of the cylinder 101 and serves to position the upper end of the spring 108. 117 indicates a by-pass valve comprising the fitting 118, the cap screw 119 serving to position the upper end of the spring 120, and the ball 121 which controls the ports to the passageway 122 leading to the interior of the pipe 110 and the nipple 111.

This completes the description of the aforesaid illustrative embodiment of the present invention. The construction of said embodiment has, it is believed, been made sufficiently clear in the foregoing description. The manner of assembling such embodiment has, it is believed, likewise been made clear in the foregoing description but may be briefly summarized as follows:

The motor 11, having been mounted on the truck 13 for movement of the device conveniently to the desired point, the eccentric housing, with the end plate 69 removed, is applied over the shaft end, the eccentric 61 slipped on over the end of the shaft, the eccentric carrying the ball bearing and the pump parts inserted in their respective cylinders, said cylinders preferably forming parts of the eccentric casing. The eccentric casing head is now screwed in place, which brings the point of the steel ball 63 against a point of the ball bearing on the eccentric, this point corresponding to the center of rotation of the motor shaft 22.

The outlet of the air pump is now connected by means of the pipe 94 with the port 45 communicating with the interior of the hollow clamping member 44. The inlet of the grease pump is connected by means of the parts 110 and 111 with the port 40 at the bottom of the tank 33 beneath the filter 39. Assuming that the tank is full of grease, with the follower 51 near the top of the tank resting on the grease, but below the port hole 46, and assuming also that the outlet pipe 114 communicating with the outlet port of the grease pump 100 is connected by means of a pipe 123 with the outlet nozzle 124, by means of which the grease or other lubricant is to be applied at the point or points desired, the device is now ready to be operated.

It may here be stated that the outlet nozzle 124 may carry an electric switch 125, held in place thereon by the rings or clamping members 126, 127. The switch may be operated by a finger 128 which is so arranged that upon pressing against the finger 128 by means of the thumb or other finger of the

operator's hand, the motor circuit is closed, while on releasing the finger 128, the motor circuit is opened. The cable 12' leading to the switch is a continuation of the cable 12 leading to the motor and has connection with any suitable source of electric power not here deemed necessary to be shown.

This completes the description of the method of assembling the aforesaid illustrative embodiment of the present invention. The manner of operating said embodiment is likewise, it is believed, sufficiently clear from the foregoing description, but may be briefly summarized as follows:

Upon closing the switch 125, which switch is preferably located near the outlet end of the nozzle 124 so that the operator may, with a single hand, close the switch and keep it closed as long as he desires and maintain the same in operative contact with the connection where the grease or other lubricant is required, the motor is set in operation, thus rotating the eccentric and the ball bearing carried thereby. This operates the pistons and plungers of the air and grease pumps simultaneously and at the same speed. However, as indicated above, the displacement of the air pump is several times, as 10, 15 or 20 times that of the grease pump, so that there is quickly built up an air pressure sufficient to feed the grease in the tank 33 into the grease pump, with the expulsion of any air pockets, the grease being forcibly ejected from the grease pump in the operation of the plunger within the same. This operation is effected without any induction or education valve in the manner already suggested above.

The operation of the pump is continued as long as lubricant is desired to be applied. Upon releasing the switch 125, the operation of the pump instantly ceases. In view of the convenient arrangement of the switch 125 with respect to the nozzle 124, the pump may instantly be put into operation and as quickly stopped by one and the same hand of the operator, while applying the outlet end of the grease nozzle to the desired point. Due to the displacement or offsetting of the axes of the pump pistons or plungers with respect to the center of rotation of the motor shaft, the speed and efficiency of the device is greatly increased.

The structures of the various pump elements are simple, easy and economical to fabricate and assemble, and combine very efficiently for the intended purpose. The device is very compact, consists of relatively few parts which may be easily and accurately assembled, and is very economical in the amount of power and labor required for its operation. By operating the two or more different types of pumps from a single driving element, such as the ball bearing eccentric described herein, great economies in power

are effected. Due also to the fact that the usual crank shaft type of operation is avoided, the usual side thrust action, which results in excessive wear and frictional losses, is avoided.

In the present embodiment, the movement of the pistons or plungers is substantially strictly rectilinear. Due also to the fact that the relative displacements of the different kinds of pumps employed are properly chosen and selected, the various types of pumps combine effectively with each other even though operated at the same speed.

The structure of the tank is such as to eliminate air pockets, deliver properly filtered grease to the system, and permit the air pressure to be applied in a uniform and highly effective manner for feeding the grease into the grease pump. The air pump is very effective and is so constructed as to permit the ready replacement of those parts of the same which will most likely become rapidly worn. The same is true of the grease pump which, by the elimination of the induction and education valves, greatly simplifies the construction of the pump and increases its life and efficiency.

By means of the device of the present invention, furthermore, very high pressures may be readily obtained which serve to force the lubricant sufficiently into contact with each part of the bearing desired to be lubricated. Other advantages of the devices of the present invention in construction, mode of assembly, operation and use will readily occur to those skilled in the art to which the present invention relates.

What I claim as my invention is as follows:

1. A pump for lubricant and the like comprising, in combination, a motor having a motor housing and a motor shaft; a tank for lubricant or the like mounted upon said motor housing and comprising a bottom member provided with an air inlet and having an inwardly extending hollow nipple the hollow of which communicates with the inner end of said air inlet, a side-wall member and an associated top member, in combination with a hollow clamping member for holding said bottom, side-wall and top members in proper relation together, the hollow of said hollow clamping member communicating adjacent its lower end with the hollow of said hollow nipple and communicating adjacent its upper end with the space within said tank; an eccentric housing, a plurality of pump casings operatively associated therewith, one of said pump casings containing the operative parts of an air pump and the other of said pump casings containing the operative parts of a fluid pump; an eccentric within said eccentric casing for operating both of said pumps; means connecting the outlet end of said air pump with the outer end of the air inlet of the bottom mem-

ber of said tank; and means connecting the inlet of said fluid pump with the outlet for lubricant or the like leading from said tank.

2. A pump for lubricant and the like comprising, in combination, an electric motor having a motor housing and a motor shaft; a tank for lubricant or the like mounted upon said motor housing and comprising a bottom member provided with an air inlet and having an inwardly extending hollow nipple the hollow of which communicates with the inner end of said air inlet, a side-wall member and an associated top member, in combination with a hollow clamping member for holding said bottom, side-wall and top members in proper relation together, the hollow of said hollow clamping member communicating adjacent its lower end with the hollow of said hollow nipple and communicating adjacent its upper end with the space within said tank; an eccentric housing, a plurality of pump casings operatively associated therewith, one of said pump casings containing the operative parts of an air pump and the other of said pump casings containing the operative parts of a fluid pump; a ball-bearing casing for operating both of said pumps; means connecting the outlet end of said air pump with the outer end of the air inlet of the bottom member of said tank; and means connecting the inlet of said fluid pump with the outlet for lubricant or the like leading from said tank.

In testimony whereof I have signed my name to this specification this 19th day of July, 1927.

ANTHONY BIZZARRI.
